UNITED STATES PATENT OFFICE.

WILLIS C. WARD, OF ORCHARD LAKE, MICHIGAN.

GAME.

Application filed March 7, 1927. Serial No. 173,493.

The invention relates to an apparatus designed to be used in the playing of bridge whist and has for its object facilitating the following of games given over radio or in printed publications. It is a further object to facilitate the analysis of the games and the playing of the same hands over a number of times without confusion. With these objects in view the invention consists in the apparatus as hereinafter set forth.

In the drawings:

Figure 1 is a diagrammatic plan view illustrating the arrangement of the card racks or holders ready for use.

Figure 2 is a perspective view of a portion of one of the holders showing the cards therein.

Figure 3 is a plan view illustrating the difference between the cards used by the several players.

Figure 4 is a perspective view indicating the difference in the several decks of cards used by each player.

In the giving of bridge whist games over radio it is usual to first designate the several players and their positions as north, east south and west. The cards dealt to each player are then called off after which the successive plays are given. To enable each of the players following the game to obtain a more comprehensive understanding of the same I have provided racks or holders each adapted to receive a plurality of full decks of cards arranged with the different suits in successive rows and the cards of each suit in sequence in its row. The corresponding cards of the several decks are placed one upon the other and any number of decks may be used. These racks or holders may be any suitable construction but as shown they are in the form of a tray A having a series of inclined steps B, B' etc., subdivided by cross partitions C so as to form compartments for holding the cards. The cards are preferably of small size so that the whole deck may be arranged within an area for convenient inspection by the player and may be accommodated by the top of an ordinary card table. Also by reason of the steps the cards of the several suits may overlap each other thereby condensing this space.

As shown in Figure 1 four of these racks are arranged for the respective use of the four players and as shown in Figure 3 the cards used by the different players are differentiated from each other. This differ-

entiation may be either by color or shade preferably by color and as indicated in the figure, the backs of the cards for the different players are marked respectively North, 60 South, East and West.

Figure 4 shows the cards of different decks used by the same player, these different decks being differentiated by a difference in color or shade. Preferably a difference in shade is used for distinguishing the several decks used by the same player and a difference in color for distinguishing the cards of the different players. The face of the cards may either be of the usual appearance or the cards may be merely designated by the symbols of the suits and the initial letters of the face cards such as A for ace, K for king, etc.

With the apparatus as described in playing the game the procedure is as follows: The cards are first arranged in the racks with backs upward displaying merely the letter which designates the position of the player as N for north, E for east; when the hands are called each of the players will reverse the called cards thereby placing it face upward in the rack. When all of the hands have been given and the cards correspondingly arranged the plays are called each of the players removing the played card from the rack and covering the tricks in the usual manner. Inasmuch however as the cards of the several players are clearly differentiated no confusion can arise 90 as to who has played any particular card.

After the deal has been played if the players desire to repeat the plays this may be readily done as the cards remaining in the rack are arranged in the same manner as those previously played. Therefore the deal may be played over as many times as there are decks in the racks and each deal is distinguished from the others by the shade of the cards.

If it is desired to conceal the cards of one player from another this may be accomplished by the inclination of the steps so that the cards in the racks are observable only by the player directly in front or suitable rack covers may be used for the same purpose. The dummy may be reversed in position to be observable by all the players.

While I have described the use of the apparatus by four players it is obvious that 110 a single player may easily follow the game if he so desires.

What I claim as my invention is:

1. A game comprising a rack for holding a plurality of full decks of cards with separate compartments for the different cards of each deck adapted to receive all of the corresponding cards in the several decks the cards of the several decks being visually differentiated upon the faces and backs thereof from those of the other decks.
- 10 2. A game comprising a rack for receiving a plurality of full decks of cards with separate compartments for the different cards of the same deck arranged in rows for the different suits and in sequence in the same suit, the corresponding cards of each deck being arranged one upon another in the same compartment and being visually differentiated upon the faces and backs thereof from each other.
- 15 3. A game comprising a rack for receiving a plurality of full decks of cards with separate compartments for the different cards of the same deck arranged in rows for the different suits and in sequence in the same suit, the corresponding cards of each deck being arranged one upon another in the same compartment and being visually

differentiated upon the faces and backs thereof from each other, said cards being reversed in their respective compartments and having indications on the back of the position of the player.

4. A game comprising a plurality of racks, one for each of the several players, each rack being adapted to receive a full deck of cards with the different suits arranged in different rows and the cards of each suit arranged in sequence and decks of cards for said racks visually differentiated upon the backs and faces thereof from each other.

5. A game comprising a plurality of racks, one for each of the several players, each rack being adapted to receive a plurality of full decks of cards with the different suits arranged in different rows and the cards of each suit arranged in sequence, the decks in the different racks being visually differentiated from each other and the decks in the same rack being otherwise visually differentiated from each other.

In testimony whereof I affix my signature.

WILLIS C. WARD.
